FRANK W. MILLER, OF CHICAGO, ILLINOIS

LOCOMOTIVE REFILLING METHOD

Application filed January 17, 1929. Serial No. 333,232.

This invention relates to locomotives refilling methods for use at locomotive terminals and is concerned particularly with methods for refilling locomotives with hot water and steam simultaneously so that when a locomotive boiler is filled to its normal water level there will be in it sufficient or nearly sufficient pressure to roll it out of the round house under its own power without first having any fire started in the fire box.

While in the past some effort has been made to refill locomotives by injecting warm water into the boilers under the injecting force of live steam supplied by the power house boiler yet these efforts have generally met with commercial failure due to the fact that they made excessive demands upon the steam produced by the power house boiler and especially so when more than one locomotive was being refilled in that manner at one time. These sudden drops in steam pressure would naturally raise havoc with steam driven equipment at the terminal and this interference has been found to be so great as to discourage the use of such equipment. A remedy which might be supplied overcoming these defects is to increase the power house boiler capacity; but naturally the installation of increased boiler capacity would involve an enormous outlay of money and in some cases might be prohibited even by lack of space. This invention makes possible the quick refilling of locomotives and production of working pressures in them, yet prevents disastrous reduction in steam pressure in the power house system.

One of the objects of this invention is to provide a refilling method for locomotive terminals which utilizes steam for direct admixture with hot refill water to make superheated refill water suited for creating working pressures immediately in locomotive boilers when used for refilling.

Another object of this invention is to provide a locomotive refill method employing a body of superheated water maintained at a high pressure into which is mixed steam at approximately the same pressure.

Another object of this invention is to produce superheated water for use in boiler refilling by adding live steam to water which is

nearly at the boiling temperature to thereby reduce to a minimum any hammering which the admixture of steam might tend to cause.

Another object of the invention is to provide storage of a large quantity of refilling water maintained at atmospheric pressure slightly below boiling with vibration of the apparatus and noise eliminated yet heating the water with high pressure steam.

Another object of this invention is to provide method for refilling a locomotive boiler with superheated water and for simultaneously as well as subsequently injecting live steam into the boiler for the purpose of creating and maintaining boiler operating pressures therein.

Other objects, advantages and capabilities are inherently possessed by this invention and will later become apparent.

Referring now to the drawing which illustrates diagrammatically apparatus for carrying out this invention there is shown a blow-off main 1 to which is connected a drop 2 at a locomotive stall and a flexible hose 3 connected to the blow-off drop and locomotive boiler for enabling the boiler to be blown off into this main. The mingled steam and water discharged from the locomotive through its respective blow-off drop passes through the blow-off main to a separator 4. In the separator, which is preferably of the centrifugal type, the water is separated from the steam and is conducted to a wash-out tank 5. This water from the wash-out tank may then be forced by the pump 6 into a wash-out main 7 thence conducted to any boiler which is to be washed out. Apparatus for regulating the temperature of the wash-out water is not a part of this invention and need not therefore be shown. The steam rising from the separator is conducted through the pipe 8 to a condenser 9 where it mingles with water admitted to the condenser through the pipe 11. This water is pumped from the refill tank by the pump 12 through the pipe 13. In practice this condenser will be located at a higher level than the refill tank so that the heated water may flow by gravity through the pipe 14 into the refill tank 15. The water level in the refill tank may be maintained by

160

adding cold water through the water level regulated valve 16.

The water from the refill tank is pumped by means of the pump 17 through the pipe 18 into a mixing box 19. The pump 17 will be controlled by means of a pressure governor 21. The pressure in the discharge pipe 18 will operate the pressure governor, the effort being made to discharge water from the pump 10 at a constant pressure of about 100 pounds.

When the water is being pumped from the mixing box 19 into the refill main 22 steam also at about 100 pounds pressure is inspirated by the water and mixes with the water 15 in the mixing box. The pressure of the steam as admitted through the pipe 23 will be regulated by a pressure regulator 24 which should be set to deliver steam at 100 pounds pressure. This regulator will prevent an undue reduction 20 of steam pressure in the main live steam line which serves the round house. A check valve 25 is placed in the line 23 to prevent any possibility of water flowing through the steam line 23 toward the pressure regulator 24. 25 The steam pressure will be preferably slightly below the water pressure.

At the end or perhaps the intermediate points in the refill main a return line 26 is connected which conducts a small amount of 30 water continuously from the refill main back under control of the valve 27 to a condenser 28 located above the water level in the refill tank. As this return flow of water passes a thermostat 29 which is located in the pipe 26, 35 the thermostat will cause a suitable thermostatically controlled valve 31 to admit more or less live steam through the pipe 32 into the condenser 28 to thereby raise the temperature of the somewhat cooled return water to the 40 temperature at which it is desired to maintain the refill water. Ordinarily this refill water should have a temperature of about 200° to 205° F.

Since the refill water will have a temperature of slightly over 200° F. there should be 45 very little hammering in the mixing box 19 when the live steam at 100 pounds pressure mixes with the water. At the same time, however, the action of the flowing water on 50 this steam will have the effect of inspirating steam in proportion to the quantity of water which is flowing through the mixing box. Accordingly the quantity of water being used for refilling any number of locomotives will 55 determine the amount of steam being used to maintain its temperature. The refill main will have a capacity of several thousand gallons of superheated water which is constantly being maintained at the desired high temperature by the continuous operation of the pump 21 and the withdrawal of water 60 through the return line 26.

Before injecting a charge of superheated 65 refill water into an empty locomotive one should of course condition the boiler plates

by first introducing a sufficient amount of steam to gradually and uniformly heat the boiler plates, to thus prevent unequal expansion of the plates. This steam may be obtained either from the live steam drop or 70 by injecting a small quantity of superheated water and permitting it to expand in the boiler into steam.

After the boiler plates are sufficiently heated, the boiler is then refilled by permitting water from the refill main to flow through the associated refill drop and refill hose into the boiler, the water being under the pressure created by the pump 17. This water drawn from the refill main will 75 ordinarily have a temperature ranging from about 250° F. upwardly. The water flowing from the refill main is replaced continuously by the water being pumped from the refill tank through the mixing box 19 where steam at about 100 pounds pressure is added thereto, thereby raising the temperature of the water. By the time the locomotive boiler has been refilled to its normal water level 80 all of the water contained therein will have a temperature of about 250° F. or more and but little more steam needs to be added thereto to produce a working pressure sufficient to enable the locomotive to be self-propelled 85 without the use of any fire in the fire box.

When any locomotive has been refilled to the proper level with this superheated refill water, having temperatures which will probably be approximately 250° F., the connection shown in the drawing may then be made, that is, the flexible hose will be connected simultaneously to the live steam line 33 and the blow-off main 1. With this connection live steam may be injected until a working pressure of perhaps 100 pounds is created in the boiler and this pressure then may be maintained by continuing the live steam connection. Should the water level, due to the condensation of steam, exceed the desired level the steam valve 34 may be shut off and the blow-off valve 35 opened permitting the pressure in the boiler to discharge the excess water into the blow-off main until the proper level is once more attained. The blow-off valve may then be closed and steam turned on again for holding the pressure. It is apparent, therefore, that the boiler may be refilled quickly and safely by means of this invention and put into condition ready for service without building any fire on the grates of the locomotive while it is still in the round house. No smoke is therefore created and the minimum amount of time is required for refilling the locomotive.

In some of the prior refilling systems the maintaining of water temperatures and the refilling of the boilers was accompanied by terrific hammering and vibration resulting in serious mechanical wear and creating constant uproar in and about the locomotive terminals.

This system provides for mixing of steam and water for the refill tank without noise or vibration; the superheating of water for the boilers is likewise accomplished quietly; and when steam is injected directly into the locomotives they have an internal temperature and pressure which makes hammering practically negligible.

The capacity of the refill tank will vary with different installations. One or more refill tanks may be used to suit conditions, but in any case the amount of refill water stored at slightly below boiling temperature should equal the total capacity of the maximum number of locomotive boilers that the system will be called upon to refill within a short period of time, so that all the boilers may be refilled efficiently and quickly.

By maintaining the water in the refill tank as close as possible to boiling most of the sludge due to the presence of water softening materials in the water will be precipitated in the refill tank rather than in the boilers. At intervals this sludge is then removed through the sludge outlet 36 shown in the drawing. Hence boilers refilled by means of this method and apparatus will not need to be blown off, washed out and refilled as frequently as has been heretofore necessary.

While it is preferable to retain the water in the refilling distributing system under a pressure of approximately 100 pounds, yet a lower pressure may be used, even as low as 75 pounds for example. In any case the steam to be mixed with the water will be regulated to have about the same or a slightly lower pressure. The water pressure of 100 pounds is to be preferred as it enables the refill water to be stored and pumped into the boilers at a higher temperature and yet the temperature difference between the steam and water entering the mixing box is not so great as to cause hammering when the mixture is made as provided by this invention. Of course the steam supplied at each locomotive stall may have any pressure in excess of the internal locomotive boiler pressure and may be added simultaneously with the superheated water or subsequently.

It should be understood that the above description illustrates but one embodiment of the invention which has been selected for illustrative purposes and that the scope of the invention, as defined in the following claims, includes other embodiments and modifications.

Having shown and described this invention, I claim:

1. A method of refilling locomotive boilers comprising heating a supply of refill water to slightly less than 212° F. and storing a quantity of it sufficient for the simultaneous refilling of a plurality of locomotive boilers, pumping the heated water as needed into a distributing system under at least 75 pounds

pressure, entraining upon the water as it enters the system a supply of steam, regulating the pressure of steam as supplied to slightly below the pressure of the water, and conducting the superheated mixture of steam and water under pressure into a boiler to be refilled.

2. A method of refilling locomotive boilers comprising heating a supply of refill water to slightly below 212° F. and storing it in a quantity sufficient for any sudden maximum demand, pumping the heated water as needed through a refilling distributing system, entraining upon the water as it enters said system a supply of steam, regulating the pressure of the steam and water separately before entrainment with the water having the higher pressure, conducting the superheated mixture into a locomotive boiler to be refilled, and supplying additional high pressure steam to the water in the boiler until a self-propelling pressure is created in the boiler.

3. A method of refilling locomotive boilers comprising heating a supply of refill water to slightly below 212° F. and maintaining a large body of it under atmospheric pressure, pumping water as needed from said body to a locomotive to be refilled, entraining into said water on the delivery side of the pump a supply of steam proportioned to the flow of water and at a pressure less than the water pressure, and supplying additional high pressure steam to the boiler until a self-propelling pressure is created therein.

4. A method of refilling locomotive boilers comprising heating a supply of refill water to slightly below 212° F. by admixture with steam blown off from locomotives, accomplishing said admixture in a condenser apart from the body of refill water thereby eliminating hammering, pumping water from the refill supply at a pressure of approximately 100 pounds to a locomotive to be refilled, entraining upon the water on the delivery side of the pump a quantity of steam, regulating the supply of steam for entrainment at a pressure below the pressure of the water, and supplying additional high pressure steam to the boiler until a self-propelling pressure is created therein.

5. A method of refilling locomotive boilers comprising heating a supply of refill water to slightly below 212° F. by admixture with steam blown off from locomotives, accomplishing said admixture in a condenser apart from the body of refill water thereby eliminating hammering, pumping water from the refill supply into a refilling distributing main under pressure of approximately 100 pounds, entraining into the water thus flowing into the main a supply of high pressure steam, regulating the supply of steam thus entrained at a pressure below the water pressure, conducting the water thus superheated into a locomotive to be

refilled, and supplying additional high pressure steam to the boiler until a self-propelling pressure is created therein.

6. A method of refilling locomotive boilers comprising heating a supply of refill water to slightly below 212° F. by admixture with steam blown off from locomotives, accomplishing said admixture in a condenser apart from the body of refill water thereby eliminating hammering, pumping water from the refill supply into a refilling distributing main under pressure of at least 75 pounds, entraining into the water thus flowing into the main a supply of high pressure steam, regulating the supply of steam to be thus entrained at a pressure below the water pressure, conducting the water thus superheated into a locomotive to be refilled, and supplying additional high pressure steam to the boiler until a self-propelling pressure is created therein.

7. A method of refilling locomotive boilers comprising heating a supply of refill water to slightly below 212° F. by admixture with blown-off steam from locomotives, accomplishing said admixture in a condenser apart from the body of refill water thereby eliminating hammering, pumping water from the refill supply into a refilling distributing main under pressure of at least 75 pounds, entraining into the water thus flowing into the main a supply of steam at a pressure below the water pressure, conducting the water thus superheated into a locomotive to be refilled, and supplying additional high pressure steam to the boiler until a self-propelling pressure is created therein.

8. A method of refilling locomotive boilers comprising heating a supply of refill water to slightly below 212° F. by admixture with blown-off steam from locomotives and high pressure steam from the round house steam supply, accomplishing both admixtures in condensers apart from the body of refill water thereby eliminating hammering, pumping water from the refill supply into a refilling distributing main under pressure of at least 75 pounds, entraining into the water thus flowing into the main a supply of steam at a pressure below the water pressure, conducting the water thus superheated into a locomotive boiler to be refilled, and supplying additional high pressure steam to the boiler until a self-propelling pressure is created therein.

In witness of the foregoing I affix my signature.

FRANK W. MILLER.
